W. N. BEST,
FIREPLACE GAS HEATER.
FILED FEB. 16, 1920.

FIG. 2.

FIG. 3. 10 21

FIG. 1.

Inventor
William N. Best
By his Attorney

G.O. Fairbank

UNITED STATES PATENT OFFICE.

WILLIAM N. BEST, OF BROOKLYN, NEW YORK, ASSIGNOR, BY MESNE ASSIGNMENTS, TO W. N. BEST FURNACE AND BURNER CORPORATION, OF NEW YORK, N. Y., A CORPORATION OF NEW YORK.

FIREPLACE GAS HEATER.

Application filed February 16, 1920. Serial No. 359,004.

To all whom it may concern:

Be it known that I, WILLIAM N. BEST, a citizen of the United States, and a resident of Brooklyn, in the county of Kings and State of New York, have invented certain new and useful Improvements in Fireplace Gas Heaters, of which the following is a specification.

This invention is an improved gas heater particularly designed for use in fire-places and as a substitute for an improvement on the ordinary gas log. Among the important objects of my invention are to secure perfect combustion of the gas, permit the gases of combustion to pass up the chimney without material loss of heat, to provide a heat absorbing and radiating surface whereby the heating effect of the burning gas is efficiently utilized and to effectively seal the fire place opening whereby escape of warm air up the chimney is prevented when the heater is not in operation.

My invention in its preferred form is very simple in construction, involves inexpensive parts easily assembled and presents an attractive appearance.

In the accompanying drawings:

Figure 1 is a front elevation showing the heater in position in a fire place opening, a portion of the heater being broken away;

Figure 2 is a vertical transverse section through the heater and adjacent fire place parts; and

Figure 3 is a top plan view of a heater on a slightly larger scale, a portion being shown in horizontal section.

In the form shown the heater includes a rectangular box or combustion chamber including a substantially imperforated metal back wall 10, substantially imperforated metal vertical end walls 11, a reticulated metal front wall 12 and reticulated metal top and bottom walls 13 and 14. These may be made of heavy sheet metal or cast iron plates and may be secured together in any suitable manner, as for instance, by flanging and bolts or rivets. The back, front, ends and top of the box or combustion chamber have linings of refractory metal. As shown, there are front and back lining plates 15 and 16 supported on the bottom 14 and held spaced apart by the refractory end lining walls 17 and the refractory top wall 18.

As shown all of the refractory lining is supported by the bottom 14 and the end and top parts fit against shoulders on the front and back parts so that no bolts or other securing means are necessary for holding the lining in position. Between each metal wall and its corresponding refractory lining there is inserted a non-combustible heat insulating packing, such for instance, as an asbestos layer 19.

The bottom of the chamber has comparatively large air inlet openings 20 and directly above these is the gas burner 21. This is shown as a single straight pipe projecting lengthwise of the combustion chamber midway between the front and back walls of the chamber. This burner pipe may have a series of gas outlet openings along the length thereof and, if desired, each opening may have a lava tip 22 to aid in the securing of perfect combustion.

The openings 23 in the top wall 13 and the corresponding refractory lining 18 are smaller than the space between said openings, and disposed on the upper surface of the top wall is a damper in the form of a longitudinal movable strip or plate 24 having openings 25 which may be moved into or out of registry with the openings 23. This damper may have a forwardly extending handle or other operating member 26 to facilitate the lengthwise movement of the damper and said movement may be guided by upstanding lugs or flanges on the top wall 13.

The front wall 12 and its refractory lining has a comparatively large number of heat outlet openings 27 which may be of any desired form and shape, and arranged in any desired order to give an artistic or attractive appearance. The top wall 13 preferably projects forwardly beyond the front wall 12 so as to form a heat deflector 28 tending to throw the heat out into the room rather than permit of its direct upward movement along the front of the fire-place casing. Also the openings 27 in the refractory lining may extend in a downwardly direction so as to also aid in deflecting the heat down toward the floor of the room.

The heater may be made of any desired size to fit freely within a fire-place opening and is preferably supported upon suitable

2
 legs 29 whereby the air may freely enter the bottom of the combustion chamber. Also the top is preferably spaced some little distance below the upper side of the fire-place opening so as to permit deflecting the gases of combustion in toward the chimney. In connection with the construction hereinbefore described, I preferably employ a closure plate 30 formed of comparatively stiff sheet metal and cut of a length and width so as to closely fit the top, bottom and sides of the fire-place and to form a fairly tight closure therefor. This closure plate 30 has an opening 31 therein at a point above the top wall 13, and secured to the front side of the closure plate 30 is a bonnet or hood 32 projecting forwardly over the top of the heater. This bonnet is connected to the closure plate along the top and ends of the opening 31 and has an open lower side directly over the gas outlet openings 23 and damper 24 of the gas heater. The lower front edge of the bonnet may engage directly with the top wall 13 in front of the damper and may have an opening through which the damper handle 26 extends. The closure plate and bonnet may be made separate from the heater and separately installed, or the plate 30 may be directly secured to the back of the heater so as to form a unitary structure therewith. In practice the gas heaters may be made in a comparatively few standard sizes and the closure plates may be cut to fit the particular fire-place openings, but with the opening 31 and bonnet 32 properly positioned to cooperate with the heater.

In my improved construction the necessary air to support the combustion may enter through the openings 20 and the gas may be burned with approximately complete combustion. The refractory lining of the combustion chamber will become heated to a very high temperature and this heat will be radiated out through the front openings 28. Furthermore the heat of the refractory lining will aid in the perfect combustion of the gas.

As is well known, illuminating gas as well as natural gas often contains sulphur compounds or other ingredients, the combustion of which produces objectionable gases. In my improved construction the damper 24 may be opened to a sufficient extent to permit the escape of the gases of combustion from the burner but without permitting any material inflow of air through the opening 28 and escape of this heated air up the chimney. When the gas is turned off, the damper 24 may be closed and all of the heat of the refractory lining will be radiated out into the room rather than permitted to escape by a current of air past the lining up the chimney. Under ordinary conditions when the heater is not in use the

damper 24 may be closed to prevent loss of warm air from the room, or may be opened to permit ventilation.

Having thus described my invention what I claim as new and desire to secure by Letters Patent is:

1. A fire place gas heater including a substantially rectangular combustion chamber adapted to be disposed within a fire place and having an apertured front wall for the escape of heat, an apertured top wall for the escape of gases of combustion, and a substantially imperforate rear wall, all of said walls being lined with refractory material, a burner within said chamber and extending lengthwise thereof at the lower portion, a closure plate in the rear of and independent of said combustion chamber, and adapted to substantially close the fire-place opening, and having an aperture therethrough above said top wall and a bonnet on the front side thereof over said aperture and projecting over the top of said combustion chamber.

2. A fire-place gas heater including a fire-place closure plate, a substantially rectangular combustion chamber in front of the same and adapted to be disposed within a fire-place having a gas burner extending lengthwise thereof at the lower portion and having a refractory lining for the front, back, top and end walls, said chamber having air inlet openings in the bottom thereof, heat radiating openings in the front wall thereof, a damper controlled outlet in the top for gases of combustion, and a hood projecting over said outlet for directing the gases of combustion to the rear of the closure plate.

3. A fire-place gas heater including a substantially rectangular combustion chamber adapted to be disposed within a fire place having parallel front and back walls lined with refractory material, a gas burner pipe extending lengthwise of said chamber between and spaced from said walls, said back wall being substantially imperforated, and said front wall having heat outlet openings and a fireplace closure plate in the rear of said chamber and having means projecting over the top of said chamber for receiving gases of combustion from the latter and directing them toward the fire-place chimney.

4. A fire-place gas heater including a substantially rectangular combustion chamber adapted to be disposed within a fire-place having an imperforated back wall and a reticulated front wall, refractory linings for said walls, refractory linings for the end and top walls and serving to space the first mentioned refractory linings apart, the top wall of said chamber having a damper controlled outlet therein and a forwardly projecting heat deflecting baffle.

5. A fire-place gas heater including a sub-

stantially rectangular combustion chamber adapted to be disposed within a fire-place having air inlet openings in the bottom, exhaust gas outlets in the top, heat outlets in 5 the front wall, the front, back, top and end walls of said chamber having refractory linings, a burner in the lower portion of said chamber, and a fire-place closure plate adapted to engage with the back wall of the

heater and having an opening therethrough 10 above the top wall of the heater and a hood extending forwardly and downwardly over the exhaust gas outlet of the heater.

Signed at New York city in the county of New York and State of New York, this 15 13th day of February, A. D. 1920.

WILLIAM N. BEST.
